UNITED STATES PATENT OFFICE

2,496,123

IONIZATION CHAMBER

Jack K. East and Spofford G. English, Oak Ridge, Tenn., assignors to the United States of America as represented by the United States Atomic Energy Commission

Application January 9, 1946, Serial No. 640,107

10 Claims. (Cl. 250—83.6)

1

The present invention relates to radioactivity responsive apparatus and more particularly to ionization chambers for measuring alpha particle emission.

In parallel plate types of alpha counters, it is frequently desirable to be able to change the geometry so that samples differing widely in activity may be counted within the preferred counting rate range. One way of changing the counting geometry without changing the mechanical geometry has been to position in the path of the alpha emission wire screens differing in mesh whereby the proportion of the particles transmitted by the screens may be varied.

The present invention relates to screen type low geometry alpha chambers and has for an object the provision of such a chamber in which the geometry is easily and rapidly changeable.

Another object of the invention is to provide an alpha chamber structure which is simple in construction, permits the ready change of samples and is convenient to clean.

Other objects and advantages of the invention will be readily apparent from the following description when read in connection with the accompanying drawing in which

Fig. 1 shows in perspective a removable end plate provided with a sample holder and a screen in accordance with the invention;

Fig. 2 is a side elevation in section of a breach type alpha chamber with the end plate of Fig. 1 in position;

Fig. 3 is a fragmentary view in section taken along 3—3 in Fig. 2; and

Figs. 4 and 5 are, respectively, perspective views of interchangeable screen members.

Referring to the drawing and particularly to Fig. 2, there is shown a chamber 10 having an upper wall 11 in which is mounted an insulated collecting electrode 12 and having a removable bottom plate 13 in screw threaded engagement with the chamber 10. A disc 14 of insulating material having integral upstanding opposed side walls 15 is secured to the upper surface of the bottom plate 13 by screws 16 to provide a seat for a U-channeled metal insert consisting of a base plate 17 and side plates 18 having outwardly extended flanges 19 shaped to conform to the side walls 15 of insulating material. This metal insert is secured in position in any suitable manner as by a screw 20 extending through a wall 15 and into a side plate 18.

The side plates 18 of the metal insert are provided with two pairs of longitudinally extending

key-ways the upper pair of which slidably support a keyed plate 21 which lies flush with the flanges 19 and which has a centrally disposed wire mesh section 22. The lower pair of key-ways in the side plates 18 slidably receive a sample support block 23 having an upright post 24, the top face of which has a sample receiving recess 25. To facilitate the insertion and removal of the block 23 it is provided with a hand grip 26 which also has a depending boss 27 adapted to abut against the front face of the base plate 17 of the metal insert thereby predetermining the position of the sample. The screen carrying keyed plate 21 is similarly accurately positioned by the provision thereon of laterally extending ears 28 which abut against the front faces of the side plates 18.

The screen carrying keyed plates of Figs. 4 and 5 are the same as the plate 21 except for the mesh size in the screen.

From the above description it will be noted that the metal insert carrying the sample support block 23 and the screen plate 21 is insulated from the bottom plate 13 and is thus adapted to become the high voltage electrode. For this purpose, one of the side plates 18 has secured thereto a projecting metal arm 29 positioned to make wiping engagement with a spring contact 30 extending into the chamber 10. The contact 30 may be connected to any suitable source of high voltage through a lead 31 passing through the wall of the chamber 10 and electrically isolated therefrom by an insulating block 32. With this arrangement the arm 29 and the contact 30 engage when the bottom plate 13 is screwed into position shown in Fig. 2 and are disengaged when the bottom plate 13 is unscrewed to remove the assembly of Fig. 1 from the chamber 10.

As described above, the invention provides a breach type screen low geometry parallel plate alpha chamber in which different known geometries may readily be obtained by inserting a proper screen member. The invention also provides a screen member as a part of the removable sample holding assembly and as a part of the high voltage electrode.

While for the purpose of illustrating the invention a particular embodiment thereof has been described it is to be understood that many modifications may be made without departing from the invention, the scope of which is pointed out in the appended claims.

We claim:

1. An ionization chamber including a pair of

spaced parallel plates adapted to define an electric field, a sample holder and a removable end plate, characterized by one of said plates being wire mesh and carried by the end plate in overlying relation to the sample holder.

2. In an ionization chamber in combination, means comprising a built in collecting electrode, and a means forming a removable end plate carrying a sample holder and a high voltage electrode, the high voltage electrode including a wire mesh screen overlying the sample holder.

3. In a breach type ionization chamber for alpha counting, a container having a collecting electrode and a removable end plate, said end plate having mounted thereon in spaced relation a perforated high voltage electrode and a sample holder, said perforate electrode overlying said sample holder.

4. In an alpha chamber the geometry of which is changed by employing screens of different mesh between an alpha source and the ionization region of the chamber, a removable bottom plate having an electrode assembly mounted thereon, said assembly comprising two spaced parallel walls having two pairs of vertically spaced horizontally extending keyways, a sample holder removably positioned in the lower pair of keyways, and a screen member removably positioned in the upper pair of keyways.

5. In an ionization chamber, in combination, a first electrode, a removable assembly forming another electrode comprising a specimen holder and an interchangeable screen member interposed between said first electrode and specimen holder.

6. In an ionization chamber, in combination, a first electrode, a removable assembly forming another electrode comprising a specimen holder and an interchangeable screen member interposed between said first electrode and specimen holder, the specimen holder comprising a unit itself removable from the assembly for changing specimens.

7. In an ionization chamber, in combination, a first electrode, a removable assembly forming another electrode comprising a specimen holder

and an interchangeable screen member interposed between said first electrode and specimen holder, and contact members engageable to place said second-mentioned electrode in a circuit when the assembly is in place in the ionization chamber.

8. In an ionization chamber, in combination with a first electrode, an electrode assembly comprising a supporting member having a base portion, a perforate member removably mounted in spaced relationship to said base portion, and a sample holder removably mounted between said perforate member and said base portion.

9. In an ionization chamber, in combination, 15 a first electrode, an electrode assembly comprising a removably mounted member adapted to carry a sample of radioactive material, and a removable perforate member interposed between said radioactive material and said first electrode.

10. In an ionization chamber, in combination, 20 a first electrode, an assembly forming a second electrode and constituting a specimen holder, said assembly being removable from the chamber and being normally spaced from said first electrode when the assembly is in place in the ionization chamber, contact members engageable to place said second electrode in a circuit when said assembly is in place in the ionization chamber, and said assembly having a member removable therefrom which forms the specimen holder.

JACK K. EAST.
